UNITED STATES PATENT OFFICE.

THOMAS AMENDOLA, OF PAWTUCKET, RHODE ISLAND.

TRUSS.

1,081,189.

Specification of Letters Patent.

Patented Dec. 9, 1913.

Application filed March 31, 1910. Serial No. 552,569.

To all whom it may concern:

Be it known that I, THOMAS AMENDOLA, a citizen of Italy, residing at Pawtucket, in the county of Providence and State of Rhode Island, have invented new and useful Improvements in Trusses, of which the following is a specification.

This invention relates to trusses for the treatment of abdominal hernia, and it has for its object to produce a device of this class which shall possess superior advantages in point of simplicity, durability and general efficiency and which may be applied and worn without discomfort.

15 A further object of the invention is to combine with the truss pad proper a suspensory bandage or support for the scrotum of simple and improved construction.

With these and other ends in view which 20 will readily appear as the nature of the invention is better understood, the same consists in the improved construction and novel arrangement and combination of parts which will be hereinafter fully described and 25 particularly pointed out in the claim.

In the accompanying drawings has been 30 illustrated a simple and preferred form of the invention, it being, however, understood that no limitation is necessarily made to the precise structural details therein exhibited, but that changes, alterations and modifications within the scope of the invention may be resorted to when desired.

In the drawing the single figure is a perspective view showing the improved truss 35 complete.

The truss pad proper A, while complete in itself, may be regarded as being composed of twin bulbs 1, 1 adapted to engage the two 40 sides of the abdomen. The pad A is provided with eyelets 2, 2 and with attaching members such as buckles 3, 3 which are secured upon the faces of the bulbs 1, 1 and with downwardly extending flaps 4, 4, the latter being also provided with buckles 5, 5. The pad A is preferably made throughout of soft leather, the bulbs 1 being formed by the introduction of suitable stuffing material, and each of said bulbs is provided with a 45 loop 6 likewise made of soft leather, the ends of the loop members being inserted through slits in the material of the pad and

joined together in rear of the front portion of the pad. Leg straps B, B, preferably including elastic portions 7 are suitably connected with the buckles 3 and 5 at either side of the pad.

C designates a back pad with which straps 8 are detachably connected by means of buckles 9, said straps preferably including elastic portions. The forward ends of the straps 8, which latter combine with the back pad to form a belt, are provided with terminal thongs 9 of chamois or other very soft leather, said thongs being inserted through the eyelets 2 of the pad A and tie together to form a bow knot 10 in front of said pad A. This manner of constructing and connecting the parts is extremely simple and convenient, and it enables the belt to be tightened or loosened, as may be required to promote the comfort of the wearer in a very convenient and satisfactory manner.

The suspensory attachment which is used 75 in connection with this device is constructed throughout of soft leather, and it includes a band 11 and a bottom piece, which latter is in the form of a cross having arms 12 and 13 which are terminally connected with the 80 band, as by stitching 14, the arms 13 being extended longitudinally and reduced in width to form thongs 17, which, after passing through the loops 6, are joined together to form a bow knot 18 which may be loosened or tightened, according to the necessities of the wearer of the truss.

As will be seen from the foregoing description, I have provided a device of extremely simple and efficient construction, 90 the parts of which are capable of being very easily and quickly adjusted to promote the comfort of the wearer. The device is intended not only for the relief but also for the prevention of abdominal hernia, and it 95 may be worn with decided advantage and comfort by the well as well as by those who are afflicted with rupture of the abdomen.

Having thus described the invention, what is claimed as new, is:—

In a device of the character described, the combination with a front pad, of a waist encircling belt supporting the same, said belt having ends projecting through the body of

the pad and joined together in front thereof, | said pad being also provided with two de-
pendent tabs, and leg encircling straps, each | of said straps being detachably connected at
5 one end with one of said tabs and at the | other end with the front face of the pad.

In testimony whereof I affix my signature
in presence of two witnesses.

THOMAS AMENDOLA.
